UNITED STATES PATENT OFFICE.

CHARLES E. LEHR, OF BETHLEHEM, PENNSYLVANIA, ASSIGNOR TO BETHLEHEM STEEL COMPANY, A CORPORATION OF PENNSYLVANIA.

CONTINUOUS HEATING FURNACE.

Application filed April 6, 1923. Serial No. 630,327.

The present invention relates to continuous heating furnaces and particularly to furnaces designed and constructed especially for the heating of metallic blanks as a step preliminary to a rolling or other operation.

In fabricating certain kinds of metallic manufactured articles for instance I beams or H beams of very light section, which have large surface areas in proportion to their volumes or cubic contents, by rolling or similar operations, it is often necessary to reheat each blank during fabrication because of the rapid loss of heat from the article due to radiation. This reheating is usually done in a furnace of the continuous type, the cool blanks being passed into the furnace at one end and removed in a heated condition at the opposite end, the heated blanks being fed immediately to the rolling mill. In one instance this reheating process has been carried out in a furnace of the continuous type in which the heating flame is projected into the combustion space or heating chamber at one end of the same, the cool blanks being inserted at the opposite end of the furnace and withdrawn from this chamber at the end adjacent the heating flame. The temperature of the blanks is thus raised gradually as they approach the outlet end of the furnace and they are withdrawn as soon as the desired temperature has been reached. Blanks having large surface areas in proportion to volumes are readily heated. As the blanks approach the outlet end of the furnace however they come in direct contact with the heating flame and as a consequence the surface of the metal is oxidized and a scale formed thereon which is undesirable, causing not only a serious loss of weight of the blank, especially where the blanks are of light weight and also objectionable in case the blanks are to undergo further rolling operations, as will be readily appreciated by one skilled in the art.

The object of the present invention is to provide a continuous heating furnace particularly adapted for use in heating metallic blanks of the character above indicated and provided with means whereby oxidation of the surface of the blank and formation of scale is prevented.

The invention may have various embodiments one of which is illustrated in the ac-

companying drawings and is herein described in detail. In the drawings:

Figure 1 is a vertical longitudinal section through the furnace:

Figure 2 is a section on line 2—2 of Figure 1, and

Figure 3 is a section on line 3—3 of Figure 1.

The roof of the furnace is indicated at 10, the floor at 11 and the walls at the inlet and outgoing ends at 12 and 13 respectively. Two tiers of oil burners are indicated at 14 and 14' respectively and are arranged to project flame into the heating chamber at one end thereof, the products of combustion being withdrawn through the flue or down-take 15 and thence conducted to a chimney 70 (not illustrated). The blanks are introduced into the heating chamber through the opening 16, which may be closed between feeding operations by the door 17, and are removed through the openings 18 at the opposite end of the furnace the blanks sliding upon skids S a number of which are arranged parallel and in the same plane, as can be seen from Figures 1 and 2. These skids slope downwardly from the inlet end of the furnace to the outlet end to facilitate movement of the blanks, which are merely pushed along these skids. Skids S are supported upon walls or piers P extending longitudinally of the furnace which piers are interrupted to provide transverse openings 20 so that the hot products of combustion may circulate freely across the bottoms of the blanks. Toward the outlet end of the furnace the tops of the piers are connected by arches 21 which prevent the flame projected into the furnace by the lower tire of burner nozzles from coming in contact with the bottoms of the blanks, and above the skids at the outgoing end of the furnace a roof is provided which comprises arches 22 springing respectively from the side walls of the furnace and abutting at their inner ends upon a water cooled longitudinally extending skew block 23 which is hung from the frame of the furnace by water cooled pipes or suspending rods 24.

Arches 22 serve to prevent the flame projected into the furnace from the upper tier of nozzles 14 from coming in direct contact with the blanks approaching this end of the furnace. The upper and lower arches there-

fore constitute muffle walls protecting the work within the muffle from flame contact.

The skids S are continuous from one end of the furnace to the other but that portion 5 of each skid which lies within the muffle is solid and preferably of nichrome while the remainder of the skid is hollow and water cooled, for instance being a pipe through which water is circulated. While the water 10 cooled skids cool the blanks at the points of contact and thereby cause black spots to occur these spots are entirely eliminated during the passage of the blank through the muffle so that upon being withdrawn they 15 are found to be uniformly heated over their entire surfaces. As the flame of the burners cannot impinge directly upon the work oxidation is prevented, saving iron which would otherwise be consumed by the flame and preventing the formation of scale. 20

To one skilled in the art the advantages of the invention will be apparent and it will also be obvious that the design of the furnace may be considerably modified without 25 departing from the spirit and scope of the invention.

Having thus described the invention what is claimed as new and desired to be secured by Letters Patent is:

30 1. A continuous heating furnace having a heating chamber provided with openings at opposite ends for the introduction and

withdrawal of blanks, means to support said blanks in their travel through the furnace, 35 ports disposed at the outlet end of the furnace so as to project the flame into the heating chamber from points above and below the said means and muffle walls disposed above and below said blank supporting means, whereby the blanks are shielded from 40 direct contact with the flame.

2. A continuous heating furnace having inlet and exit openings for material, sources of heat arranged adjacent to the exit opening, skids extending longitudinally of the 45 furnace and shields for protecting the skids and the material supported thereon near the exit opening, each skid comprising a water-cooled portion in the unshielded regions of the furnace and a solid portion in the shielded 50 region.

3. A continuous heating furnace having inlet and exit openings for material, sources of heat arranged adjacent to the exit opening, skids extending longitudinally of the 55 furnace and shields for protecting the skids and the material supported thereon near the exit opening, each skid comprising a water-cooled portion in unshielded regions of the furnace and a solid portion of heat resistant 60 material in the shielded region.

In testimony whereof I hereunto affix my signature.

CHARLES E. LEHR.
